TIMER

**Thomas A. Daly, Sharpsville, and Harry A. Gill,
Sharon, Pa., assignors, by mesne assignments,
to the United States of America as represented
by the Secretary of the Navy**

Application October 29, 1945, Serial No. 625,432

4 Claims. (Cl. 161—1)

1

Our invention relates to shaft-driven timers for torpedoes, but more generally to devices responsive to selected numbers of revolutions of a shaft.

In the torpedo art, it is important both for torpedo exercise runs as well as war shots that certain devices are, respectively, set in operation at the end of selected time intervals, after firing or launching of a torpedo. Delicate clock mechanisms do not readily withstand the shocks occurring at launching of an aerial torpedo or for that matter occurring at the firing of a torpedo from a tube.

One broad object of our invention is the provision of rugged and reliable timing means for torpedoes or other devices.

Another broad object of our invention is the provision of reset-limit switching means for torpedoes or other devices for controlling the sequence of operation of certain elements of torpedoes, or such other devices.

A specific object of our invention is the provision of means operable from the propulsion shaft of a torpedo and thus responsive to the number of revolutions of the shaft for controlling the sequence of operation of certain electrically actuated elements of the torpedo.

The objects specifically recited are merely illustrative. Other objects and advantages will become more apparent from a study of the following specification and the accompanying drawings, in which:

Figure 1 is a plan view of our invention;

Fig. 2 is a front view of our invention with certain parts broken away to more clearly show the construction thereof;

Fig. 3 is a diagrammatic showing of our invention; and

Fig. 4 is a right end view of our invention taken from Fig. 2 with parts broken away to more clearly show the construction.

As seen in Figs. 1, 2 and 4, our invention comprises a two-piece U-shaped frame 1 which is rigidly secured to the frame structure of a torpedo, or other device, by suitable bolts disposed through the openings 2 and 3 in the bottom portion, or bight portion, of the frame 1.

The frame thus provides a pair of parallelly disposed side plates between which we mount the movable elements and certain other stationary elements of our invention. The side plates are held in fixed spaced relation by the bolts 4, 5 and 6, provided with the cylindrical sleeve-like spacers shown on these bolts, and by rectangular blocks 7, 8, 9 and 10 provided with the threaded

2

outer ends for the reception of the lock washers and nuts shown.

5 A pair of strips 11 and 12 of insulating material bridge the blocks 9 and 10 and a pair of strips 13 and 14 of insulating material bridge the blocks 7 and 8. Each of the strips 11, 12, 13 and 14 carries a micro-switch, or similar switch, comprising the switches 15, 16, 17 and 18. These switches are provided with connecting terminals 10 19 and 20, 21 and 22, 23 and 24, and 25 and 26, respectively, for connection to the electrical elements of the torpedo to be energized electrically in a sequence selected. The switches each have resilient actuating strips as those shown at 27 15 and 28 for operating the snap-action contact mechanisms, such as 29 and 30 shown in Fig. 2.

The resilient elements, as 27 and 28, are operated by the buttons 31, 32, 33 and 34 adjustably mounted on the pivoted lever arms 35, 36, 37 and 38. Lever arms 35 and 37 are pivoted on the bearing shaft 40 disposed in the side walls of frame 1 and lever arms 36 and 38 are pivoted on the bearing shaft 39 also disposed in the side walls of the frame 1.

25 The lever arms are so disposed on their pivots, or bearing shafts 39 and 40, that their free ends all fall nearly in the same vertical plane including the axis of the sleeve shaft 41.

1 The sleeve shaft 41 rotates on the stationary
- 30 bearing blocks 42 and 43 held in spaced relation
by the spacer 46. A torsion spring 44 is disposed
about the spacer 46. The spring 44 has its left
end, as seen in Fig. 4, secured to plate-like left
end 45 of the sleeve shaft 41 and has its right end
35 secured in aligned openings in the block 42 and
the side wall of the frame. Clockwise rotation
of the sleeve shaft 41, as seen in Fig. 2, will thus
wind this spring up to a greater degree than its
original wind-up tension. The original wind-up
40 tension of spring 44 is so selected that when the
shaft is released, the shaft and the elements car-
ried thereby are positively rotated in a counter-
clockwise direction till the projection 47 engages
the stop 48 mounted in frame 1.

45 The sleeve shaft 41 carries three rings 50, 51 and 52, which have limited individual axial movement with reference to the shaft 41 but are held against rotation on the shaft by the key 53. A flat ring 54 of insulating material, as some phenolic resin product, fiber board, or hard rubber, is disposed between the disk-like end 45 and ring 50, and similar rings 55 and 56 are disposed between rings 50 and 51, and 51 and 52, respectively.

ries for actuating the lever arms 35 and 36 through rollers mounted in the free ends of these lever arms. Ring 56, at its outer periphery, terminates in two parallelly disposed cam surfaces for activating the lever arms 37 and 38 through rollers mounted in the free ends of these lever arms. To provide initial circumferential adjustment of the cams about sleeve shaft 41, the rings 54, 55 and 56 are free to rotate on the sleeve shaft. When adjusted to the desired position the bolts 57 and 58 are tightened to thus clamp the cam rings 54, 55 and 56 between the end 45 and rings 50, 51 and 52. The bolts have their left ends threaded into the end 45 and through suitable holes in rings 50, 51 and 52 and suitable arcuate slots in the cam rings 54, 55 and 56 hold the rings in assembled relation. Since the rings 50, 51 and 52 are keyed to the sleeve shaft 41 a unitary rotatable assembly is provided.

The ring 51 is provided with a peripheral flange to which the worm wheel 60 is bolted as shown. The worm wheel 60 is disposed to be in mesh with the worm 61 mounted on a transmission shaft 63 which also carries the worm wheel 62.

This transmission shaft 63 is mounted in a cradle bearing 64 which is rigidly secured to the counter shaft 65 rotatably mounted in a suitable bracket, as 66, on the frame 1. The cradle bearing 64, as seen in Fig. 4 is provided with a handle-like projection 67 at the left, which bears on the upper edge of the opening in the frame and thus fixes the gearing clearance between worm 61 and worm gear 60. A relatively strong compression spring 68 is disposed between the bottom of the frame and the projection 67 and normally holds the worm wheel 60 and worm 61, and the worm wheel 62 and the worm 69, mounted on the torpedo propulsion shaft 70, in mesh.

If the sleeve shaft 41 is to be released, the projection 67 may be manually depressed or similarly actuated through rotation of shaft 65. When the timer is in position on the torpedo, the square end 71 of shaft 65 is actuated by a suitable wrench from the outside of the torpedo. By thus actuating the shaft 65 in the direction indicated by the arrow adjacent to shaft 65, the worm wheel 60 is released and in consequence the spring 44 resets the timer to the position shown in Fig. 2.

When the torpedo is to be fired, the timer is first reset by operation of shaft 65. The cams then take substantially the position shown schematically in Fig. 3. As soon as the torpedo is fired, the propulsion shaft starts operating and thus, in view of the considerable gear reduction, slowly drives worm wheel 60 in the direction indicated.

Cam, or ring, 54, at from 170 to 360 yards of torpedo travel, depending on the adjustment of the cam 54, actuates the switch 18 to effect closing of the arming circuit for the warhead exploder.

Cam, or ring, 55, at 212 to 400 yards of torpedo travel, also depending on the adjustment of cam 55, effects the operation of switch 16 to effect the energization of certain other circuits in the torpedo.

The right-hand cam portion of ring 56 is useful during exercise runs only and effects the opening of the circuit for the main driving motor. This operation is usually effected at from 1000 to 2000 yards of torpedo travel. The left-hand

cam portion of ring 56 effects the energization of the ballast-liquid-blowing-circuit at about thirty-five yards before the right-hand cam portion of ring 56 effects its operation.

While we have shown and described but one modification of our invention, we do not wish to be limited to the specific showing made but wish to be limited only by the scope of the claims hereto appended.

We claim as our invention:

1. In a system of control for a torpedo having a propulsion shaft set in operation when the torpedo is launched, in combination, a propulsion shaft, means for rotating the propulsion shaft, a timer shaft, a stop; a stop-engaging element on the timer shaft; resilient means for biasing the stop-engaging element against the stop; a transmission gear for operatively coupling the timer shaft to the propulsion shaft

20 of the torpedo; a switch; a cam on the timer shaft for operating the switch after a predetermined rotation of the propulsion shaft; and means for disengaging the transmission gear from the timer shaft whereby the resilient means operates the timer shaft to its initial position so that the stop-engaging element engages the stop.

2. In a system of control, in combination, a driven shaft; a worm on the driven shaft; a timer 30 shaft; a worm wheel on the timer shaft; a transmission shaft having a worm wheel meshing with the worm on the driven shaft and a worm meshing with the worm wheel on the timer shaft; a countershaft disposed parallel to the transmission

35 shaft; a cradle bearing for the transmission shaft pivotally mounted on the countershaft; resilient means biasing the cradle bearing in a direction to effect movement of the transmission shaft parallel to itself to cause said meshing engagement between the worm and worm wheel on the transmission shaft and the worm and worm wheel on the driven shaft and timer shaft, respectively; means for moving the cradle bearing to effect unmeshing of the respective worms

40 and worm wheels; resilient means for rotating the timer shaft to an initial position upon effecting the said unmeshing of the respective worms and worm wheels; cam means on the timer shaft, and switching means operable upon rotation of 45 the timer shaft through a given angle from its initial position.

3. In a system of control for a torpedo having a conventional housing and propulsion shaft, in combination, a worm on the propulsion shaft; 50 a timer shaft substantially parallel to the propulsion shaft; a worm wheel on the timer shaft; a transmission shaft substantially normal to the timer shaft and propulsion shaft; a worm and worm wheel on the transmission shaft normally

55 meshing, respectively, with the worm wheel and worm on the timer shaft and propulsion shaft; a cradle bearing for the transmission shaft; a counter shaft disposed in parallel relation to the transmission shaft, said cradle bearing being rigidly secured to the counter shaft, whereby

60 by the rotation of said counter shaft the cradle bearing is shifted to swing the transmission shaft parallel with respect to itself to break the operative connection between the propulsion shaft and the timer shaft; biasing means for the cradle bearing to normally maintain the operative relation between the propulsion shaft, transmission shaft, and timer shaft; means engageable from the outside of the torpedo housing for rotating 65 the counter shaft against its biasing means; bias-

70

ing means for the timer shaft for rotating said timer shaft to an initial position when said counter shaft actuated to operate the cradle bearing against its bias; cam means on the timer shaft; and switching means operated by the cam means.

4. In a system of control for a torpedo having a conventional housing and propulsion shaft, in combination, a worm on the propulsion shaft; a timer shaft substantially parallel to the propulsion shaft; a worm wheel on the timer shaft; a transmission shaft substantially normal to the timer shaft and propulsion shaft; a worm and worm wheel on the transmission shaft normally meshing, respectively, with the worm wheel and worm on the timer shaft and propulsion shaft; a cradle bearing for the transmission shaft; a counter shaft disposed in parallel relation to the transmission shaft, said cradle bearing being rigidly secured to the counter shaft, whereby, by the rotation of said counter shaft, the cradle bearing is shifted to swing the transmission shaft parallel with respect to itself to break the operative connection between the propulsion shaft and the timer shaft; biasing means for the cradle bearing to normally maintain the operative relation between the propulsion shaft, transmission shaft, and timer shaft; means engageable from the outside of the torpedo housing for rotating

the counter shaft against its biasing means, biasing means for the timer shaft for rotating said timer shaft to an initial position when said counter shaft is actuated to operate the cradle bearing against its bias; a plurality of circumferentially adjustable cams on the timer shaft; a plurality of switching means; and means associated with each cam and each switching means for operating the switching means in a selected sequence after selected numbers of revolutions of the propulsion shaft.
